UNITED STATES PATENT OFFICE.

CHARLES E. WARNER, OF WAVERLY, KANSAS.

WIRE FENCE.

SPECIFICATION forming part of Letters Patent No. 607,203, dated July 12, 1898.

Application filed November 30, 1897. Serial No. 660,260. (No model.)

To all whom it may concern:

Be it known that I, CHARLES E. WARNER, a citizen of the United States, residing at Waverly, in the county of Coffey and State of Kansas, have invented a new and useful Wire Fence, of which the following is a specification.

My invention relates to wire-fence construction particularly adapted for use in connection with stock-fences; and the object in view is to provide a simple and efficient tie or connection between twisted or plural strand runners and the stays by which they are intersected.

15 Further objects and advantages of this invention will appear in the following description, and the novel features thereof will be particularly pointed out in the appended claims.

20 In the drawings, Figure 1 is a view of a section of fence constructed in accordance with my invention. Fig. 2 is a detail side view of the improved tie, showing the engaged runner in section. Fig. 3 is a detail view in perspective of the tie and the engaged runner-strands.

25 Similar numerals of reference indicate corresponding parts in all the figures of the drawings.

In order to provide a lock or connection between plural-strand runners and the intersecting stay, whereby the runner and stay are held from relative displacement and whereby at the same time the thickness of the fence-fabric as woven for sale is but slightly increased over the thickness of the runners at

35 those points where the runner-strands intersect in a horizontal or transverse plane, I have adopted a lock of a construction of which the essential feature resides in two oppositely-extending closed loops centrally arranged in a common vertical plane with the center of the runner, said loops being arranged in contiguous but different transverse planes. It is common to weave or interlock a stay-wire with a

40 plural-strand runner in order to prevent longitudinal displacement of the stay; but in practice it has been found to be a serious disadvantage that this lock adds greatly to the thickness of the fabric at these points of connection, and hence when rolled or packed for shipment the bulk is vastly increased over that of other forms of wire fabric, or over that

which it would have if it were not for the projection of the lock beyond the opposite side faces of the runners. It is therefore desirable to form a lock which is not only efficient and is so interwoven with the runner as to prevent displacement, but to construct said lock of a transversely-flat form, which exceeds but slightly, if at all, the transverse thickness of the runner itself. I have been able to accomplish this object by connecting the stays with the runners at those points of the latter where the intertwined strands are arranged in common vertical planes and by using for the stays a lighter or smaller gage wire than that which is employed for the runner-strands. Where the runner-strands intersect in a horizontal or transverse plane, the runner is equal in thickness to double the thickness of one of the strands, whereas at those points of the runner where the strands intersect in a vertical or longitudinal plane the runner is in thickness equal to only one strand. Thus by connecting the stay-wire with the runner at those points where said intersection occurs in a vertical or longitudinal plane and by arranging the portions of the stay-wire which are disposed at the sides of the runner-strands in different transverse planes or out of transverse alignment the combined thickness of the runner and stay is only equal to double the thickness of a runner-strand, and hence only equal to the thickness of the runner at the points where its strands are intersected in a horizontal transverse plane.

In carrying out my invention I provide the stay-wire 1 with a double or gooseneck bend to form upwardly and downwardly extending loops 2 and 3, which are counterparts in construction and shape and of which the sides are drawn toward each other after engagement with the runner-strands to form closed eyes, through which said runner-strands extend, this transverse contraction of the loops being efficiently accomplished in practice by pinching the loops after the interlocking operation has been completed; but it is desirable not only to engage the oppositely-extending loops of the lock with the runner-strands at points where the latter are arranged in a common vertical plane, but to dispose the loops in different though contiguous trans-

verse planes, whereby only one thickness of the stay-wire projects transversely at any point beyond the side of a runner-strand. In other words, it is necessary, to avoid doubling the thickness of the stay-wire at any point, to prevent projection beyond the runner at those points where the strands of the latter intersect each other in a horizontal or a transverse plane. Thus the lock embodying my invention consists of oppositely-extending single-strand-engaging closed loops arranged in different transverse planes, the contiguous portions of the stay integral with which said loops are formed being also arranged in different transverse planes from the loops. By closing the loops to form eyes, as above described, the accidental displacement of the runner-strands therefrom is prevented, and in addition to this the eyes may be disposed in the common vertical or longitudinal plane of the runner-strands at their points of intersection in said vertical or longitudinal plane. The thickness of the fabric is approximately uniform throughout, and the frictional contact of the eyes comprising the lock with the runner-strands prevents displacement of the stays longitudinally of the runners, even through an interval limited by the length of the twists formed by the runner-strands. In other words, I do not depend upon the contiguous twisted or transversely-intersecting portions of the runner-strands to prevent excessive displacement of the stays, but particularly upon the frictional contact of the stay-loops with the strands, and it is obvious that the necessary frictional contact to attain this object is secured by the closing of the loops.

A further advantage attained by the peculiar construction of lock as above described resides in the fact that the strand-engaging eyes of the stay are arranged approximately in the line of the contiguous straight portions of the stay or the deflection of the centers of the eyes from the line of the straight portions of the stay is so slight that longitudinal strain upon the portions of a stay upon opposite sides of a lock or above and below the same will not have the effect of distorting the lock by the partial or complete straightening of the loops constituting such lock.

I have shown the improved stay and runner-engaging lock as applied to a fence having smooth intermediate runner-strands and barbed marginal or selvage runners; but it will be understood that the improvement is also applicable to any other form of plural-strand runner, provided the engagement of the closed loops of the stay can be accomplished at such a point in the runner as to lie contiguous to runner-strands which intersect in a vertical or longitudinal plane. It will be understood, furthermore, that I do not desire to be understood as confining myself to the use of the lock as a means of attachment to the top and bottom runners, but more par-

ticularly to the intermediate runners, and that any other suitable means of engagement of the extremities of the stays may be adopted—such, for instance, as wrapping the ends of the stays around the runners. It will be noted, furthermore, that the intermediate runners instead of being of the continuously-twisted construction shown in connection with the marginal or selvage runners (and by "continuously-twisted" I mean to imply that the runner-strands are intertwined in a continuous direction, whether the selected direction be to form a right-hand or a left-hand twist) are constructed with an alternately-reversed twist. In other words, between two contiguous stays an intermediate runner has its strands twisted to the right, while in the adjoining space, between one of said stays and the next one, an opposite or left-hand twist is formed. The effect of this is to form opposite upwardly and downwardly extending loops 4 and 5, lying approximately in a common vertical plane, the centers of the loops being accurately in a common vertical plane and being spaced apart a sufficient distance to allow the connecting portion of the tie to pass therebetween. In addition to forming an efficient connection I have found this construction adapted for manufacture with facility and economy.

Having described my invention, what I claim is—

1. A wire-fence fabric having twisted plural-strand runners, and connecting-stays intersecting the runners at points where the runner-strands are in common longitudinal planes, and connected therewith by means of a lock consisting of oppositely-extending closed single-strand-engaging loops forming eyes which are axially disposed in the common longitudinal plane, substantially as specified.

2. A wire-fence fabric having twisted plural-strand runners, and connecting-stays intersecting the runners at points where the runner-strands are in a common longitudinal plane, and provided at each point of intersection with a lock consisting of oppositely-extending closed single-strand-engaging loops arranged in different transverse planes and axially in a common longitudinal plane, the contiguous portions of the stay being disposed at the sides of the runner-strands in different transverse planes from said loops and in the same longitudinal planes as those sides of the loops which are on the same sides of the runner-strands, substantially as specified.

In testimony that I claim the foregoing as my own I have hereto affixed my signature in the presence of two witnesses.

CHARLES E. WARNER.
